UNITED STATES PATENT OFFICE

JOHN J. MANNION, OF FAIR OAKS, PENNSYLVANIA

GROUND RESERVOIR

Application filed September 26, 1928. Serial No. 308,570.

This invention relates to ground reservoirs or resistors for radio circuits, and has for its object the provision of a reservoir element adapted to be inserted in the grounded side 5 of a radio circuit and to so increase the ground capacity of the circuit that the capacity and close tuning of the radio receiver is materially increased and improved quality of reception results.

10 Experience has shown that by the use of the ground reservoir of this invention the range of a radio receiver can be materially increased and in some instances almost doubled, with all conditions remaining constant except for the change in the ground connection.

15 The theory upon which the novel results of this apparatus works is not certain. It is thought that this apparatus serves as a capacity reservoir for the high frequency radio currents, that is, due to its novel construction, it has a capacity many times greater than the ground wire with which it is in series and, therefore, it can store up rushes of current and either dissipate said current or permit it to pass out through the ground when the flow is less.

20 Another theory advanced for the function of the apparatus of this invention is:—for an electrical circuit, of which this resistor forms a part, and assumed at a given instant to have a resistance of R —ohms; this same circuit having an inductance of L —henrys, and a 25 capacity of C farads, the number of waves per second may be calculated from the relation—

$$N = \frac{1}{628} \sqrt{\frac{1}{LC} \frac{R^2}{4L^2}}$$

30 If R^2 is less than

$$\frac{4L}{C}$$

35 the circuit is capable of acting as a source of or a detector for oscillations. In any case, in practice, R is usually very small.

40 The above being true, then the apparatus of this invention, due to its novel construction, probably serves as a sensitive type of skin-effect resistance.

Either of the above theories of operation may be correct, or the novel results obtained may be the result of an entirely different theory. This I am unable to tell, but, however, it is certain that the use of this novel element in series with the ground wire of any radio set will greatly improve the range and quality of reception.

45 In the drawings:

50 Figure 1 is a plan view of a reservoir member constructed in accordance with this invention.

55 Figure 2 is a longitudinal sectional view through the body thereof.

60 Figure 3 is a transverse sectional view taken on the line III—III of Figure 2.

65 Figure 4 is a sectional view through one of the cap members.

70 Figure 5 is an enlarged transverse view through one of the wires forming the capacity body.

75 Referring more particularly to the drawings, the letter A designates the shell of the reservoir or resistor member as a whole which is composed of a tubular member having a core portion of ferrous metal 2 and an enveloping covering or plating of copper and silver 3.

80 The ferrous metal core 2 has a relatively low conductivity, while the platings or coverings of copper and silver have a relatively high conductivity. The platings of copper and silver are preferably deposited by electrolysis and while the silver coating alone, which has a very high conductivity, would be sufficient insofar as the operation of the device is concerned, this metal cannot be satisfactorily deposited directly on the ferrous metal core and, therefore, it is found desirable, if not necessary, to first deposit a coating of copper on the ferrous metal and then deposit the silver on the copper.

85 A series of copper wires 4, having a covering of silver plate 5, are arranged longitudinally within the shell A so as to form a single layer around its inner circumference.

90 A cap member B is removably secured on each end of the shell A. The cap members B are composed of a ferrous metal core 6 hav-

ing copper and silver plated enveloping coatings or coverings 7 deposited by electrolysis.

As shown, these caps B are threaded internally and screw on the threaded ends of the 5 shell A, the threads being cut before the shell and caps are plated.

Attaching clip members 8 are secured to each of the cap members B by bolts 9, which bolts extend through the caps an appreciable 10 distance and are locked in position by nuts 10. Clamping or wedging disks 12 are mounted on the inner ends of the bolts 9 and are adapted to be forced into the circle of 15 wires 4 so as to force said wires into engagement with the shell A and form an electrical connection with said wires 4, said shell A and said cap members B.

In operation, one end of the reservoir or 20 resistor apparatus of this invention is preferably connected to the ground terminal of a radio set by a short length of wire leading from one of the attaching clips 8, while the other end is connected to a ground wire by the other clip 8.

While I have shown one specific embodiment of my invention which is, as far as known to me, the best embodiment thereof, it 25 will be understood that I do not wish to be limited thereto, since various modifications 30 may be made which will give at least some degree of the results obtained by the form herein disclosed. For instance, the shell A may be made from copper or brass and silver 35 plated, if desired, or the shell may be made of a non-conducting material, and while the results, as far as known by me, will not be as good as those obtained by the form of the invention herein disclosed, nevertheless radio 40 reception will be materially improved.

It will also be noted that at least fair results may be obtained from apparatus constructed like that herein disclosed but with the silver plating omitted.

As stated in the forepart of this specification, the theories of operation of this apparatus are the best I now know, and while such theories may be wrong, nevertheless experience has shown that radio sets equipped with 45 this apparatus show a marked improvement both in close tuning and quality of reception. In some cases under identical conditions a "Radiola No. 17" radio, when equipped with this apparatus, had such improved tuning 55 qualities that substantially double the number of stations were tuned in than was possible with the same ground connection without the apparatus of this invention being in series therewith.

I claim—

1. A ground resistor member for use in the ground circuit of a radio, said resistor comprising a capacity body composed of a plurality of parallel copper wires of round cross-

section and having an integral surface coating of a rare metal having a materially higher conductivity than copper, means for forming an electrical contact between all of said wires at each end, means for connecting a wire from the ground side of a radio set to one end of said wires, and means for connecting a grounded wire to the other end of said wires, said capacity body having less resistance and materially greater capacity 75

2. A ground resistor member for use in the ground circuit of a radio, said resistor comprising a capacity body composed of a plurality of parallel copper wires of round cross-section and having an integral surface coating of a rare metal having a materially higher conductivity than copper, a tubular metal shell surrounding said body of wires, said shell having an integral surface coating on both its inner and outer surfaces of a rare metal having a materially higher conductivity than copper, means for closing each end of said shell and for forcing said wires into electrical contact with said shell at each end thereof, and means for connecting a wire from the ground side of a radio to one end of said shell, and means for connecting a grounded wire to the other end of said shell, said shell and said capacity body of wires having less resistance and materially greater capacity than said ground wire. 85

3. A ground resistor member for use in the ground circuit of a radio, said resistor comprising a tubular rigid shell, a capacity body composed of a series of copper wires of round cross-section arranged parallel to each other and to the axis of said shell to form a layer around the interior of said shell, means for closing each end of said shell and for forcing said wires into electrical contact with said shell at each end thereof, means for connecting a wire from the ground side of a radio to one end of said shell, and means for connecting a grounded wire to the other end of said shell, said shell and said capacity body of wires having less resistance and materially greater capacity than the ground wire. 100

4. A ground resistor member for use in the ground circuit of a radio, said resistor comprising a tubular shell, a capacity body composed of a series of parallel copper wires of round cross-section arranged to form a layer around the interior of said shell, said wires having an integral surface coating of a rare metal having a materially higher conductivity than copper, means for closing each end of said shell and for forcing said wires into electrical contact with said shell at each end thereof, said shell having an integral surface coating on both its inner and outer surfaces of a rare metal having a materially higher conductivity than copper, means for connecting a wire from the ground side of a radio to one 110

end of said shell, and means for connecting a grounded wire to the other end of said shell, said shell and said capacity body of wires having less resistance and materially greater capacity than the ground wire.

In testimony whereof, I have hereunto set my hand.

JOHN J. MANNION.
